UNITED STATES PATENT OFFICE.

THOMAS HUNT, OF NEW YORK, N. Y.

IMPROVEMENT IN TRAVELING-TRUNKS.

Specification forming part of Letters Patent No. 96,236, dated October 26, 1869.

To all whom it may concern:

Be it known that I, THOMAS HUNT, of the city and State of New York, have invented and made a new and useful Improvement in Traveling-Trunks; and I do hereby declare the following to be a full, clear, and exact description of the said invention, reference being had to the annexed drawings, making part of this specification, wherein—

Figure 1 is a vertical section of said trunk as opened, and Fig. 2 is an elevation of the trunk with the top opened and the swinging front section turned up into its place.

Similar marks of reference denote the same parts.

This trunk is designed with special reference to containing various articles of apparel, toilet, useful and ornamental articles connected with a lady's wardrobe, and required in traveling to be contained in easily-accessible positions, so any article can be readily got at without having to unpack but little of the trunk. My trunk is constructed so as to attain the foregoing objects, and at the same time the trunk is made very much stronger than heretofore, and it can be used for a seat or for a writing-table, thus greatly increasing its usefulness; especially in the contracted spaces in state-rooms and hotels usually allotted to travelers.

In the drawings, *a* is the bottom; *b*, the front; *c*, the back, and *d d* the ends, forming the lower part of the trunk; but, instead of being of a simple box shape, as usual, the front *b* and sides *d d* are partially removed to receive the section *e*, that is hinged at *f*, and contains a drawer, *g*.

The lower part of the trunk is closed across the top by the partition *h*, which strengthens the trunk and prevents the ends being pressed in by any weight in transportation. The bottom of the trunk is still further strengthened by the partition *k*, attached on the line of the angle of the portion removed from the ends *d d*, and between these partitions *h* and *k* the sliding drawer *l* is introduced; and *i* is a sliding cover that can be pushed back beneath *k* to give access to the bottom part of the trunk, into which large or heavy articles can be securely packed. It will now be seen that

this construction of the base of the trunk renders the same very strong, because the wood-work or frame of the trunk makes a greater number of firmly-secured angles and corners than heretofore, and, in fact, makes the bottom a trunk that would be sufficiently strong to be used without any lid, the swinging section *e* being provided with a lock at *n*. When the section *e* is closed, the bottom portion of the trunk can be used as a table or seat. When the section *e* is swung over, as seen in Fig. 1, that part, *e*, might be used as a low seat, and the front of the drawer *l* as a back to the seat, or the top of the partition *h* can be used as a writing-table. Straps are to be provided at the ends of the trunk to hold the section *e* to its place, if desired.

The top portion, *w*, of the trunk is hinged at *o* to the bottom, and its interior is separated by the divisions *p* and *q*, so as to receive the sliding drawers *r* and *s*; and *t* is a hat-case, hinged at *u*, so as to swing out, in order that the lid *v* of said hat-case may be lifted. This case I might be divided by transverse partitions, so as to contain several separate hats or head-dresses for ladies.

By constructing the trunk in the manner before described the various partitions add greatly to the strength of the lid and the bottom, and at the same time facility is given for getting at any article with but little unpacking, and the trunk can be used for a seat or table.

When the trunk is closed, the parts prevent dust or water passing into the trunk, and the usual exterior appearance of the trunk is maintained.

I am aware that a trunk has been made with a section in the front that will fold upward when the lid is raised, so as to form a series of shelves. This construction renders it necessary to have locking-bars extending across the front of this section from the lid to the bottom part of the trunk. In my improvement the section, being hinged at the front and lower edge, forms a strong joint at this part, and the lid, when closed, covers the moving edge of the section and the lock by which it is secured.

What I claim as my invention is—

Hinging the lower portion of the section *e* to the front of the trunk at *f*, and applying the lock or hasp at the upper portion, so as to be covered by the lid *w*, when the trunk is closed, substantially as set forth, and in combination therewith, the drawer *l* and sliding cover *i*, arranged in the manner and for the purposes specified.

In witness whereof I have hereunto set my signature this 12th day of July, 1869.

THOMAS HUNT.
